The ornamental design of a facial recognition security device, as shown and described.

DESCRIPTION

FIG. 1 is a front, top and right side perspective view of a facial recognition security device according to a first embodiment of the present invention;

FIG. 2 is a left side elevational view of the facial recognition security device of FIG. 1;

FIG. 3 is a right side elevational view of the facial recognition security device of FIG. 1;

FIG. 4 is a front elevational view of the facial recognition security device of FIG. 1; and,

FIG. 5 is a front, bottom and left side perspective view of the facial recognition security device of FIG. 1.

The broken line showing of vents and a cut out section is included for the purpose of illustrating portions of the "article" and forms no part of the claimed design.
